UNITED STATES PATENT OFFICE.

LOUIS GOHLKE AND ROBERT W. IRWIN, OF GRAND RAPIDS, MICHIGAN,
ASSIGNORS TO THE GRAND RAPIDS SCHOOL FURNITURE COMPANY,
OF SAME PLACE.

DESIGN FOR A CHAIR-BACK.

SPECIFICATION forming part of Design No. 30,138, dated February 7, 1899.

Application filed October 5, 1898. Serial No. 692,757. Term of patent 14 years.

To all whom it may concern:

Be it known that we, LOUIS GOHLKE and ROBERT W. IRWIN, citizens of the United States, residing at Grand Rapids, in the county 5 of Kent and State of Michigan, have invented and produced a new and original Design for Chair-Backs, of which the following is a specification.

The design is illustrated in the accompanying drawings, in which—

Figure 1 is a front elevation of the back. Fig. 2 is a plan view of Fig. 1. Fig. 3 is a side elevation of the design.

The design presents as the leading feature 15 the configuration of the back.

As shown in the figures, the back of the chair is of curved shape extending from side to side, and the outer side edges of the back curve outwardly, increasing the width of the back at the top, as shown at *a*. The back is 20 shown at A, and it is inclined, as shown in Figs. 2 and 3, rearwardly and upwardly.

What we claim is—

The design for a chair-back as herein shown and described.

LOUIS GOHLKE.
ROBERT W. IRWIN.

In presence of—

L. T. GIBSON,
A. D. LINN.
